UNITED STATES PATENT OFFICE.

JAMES TABB DONAHOO, OF EDGAR, NEBRASKA.

WATER-TANK.

SPECIFICATION forming part of Letters Patent No. 749,273, dated January 12, 1904.

Application filed February 25, 1903. Serial No. 144,932. (No model.)

To all whom it may concern:

Be it known that I, JAMES TABB DONAHOO, a citizen of the United States, and a resident of Edgar, in the county of Clay and State of Nebraska, have made certain new and useful Improvements in Water-Tanks, of which the following is a specification.

My improved tank is so constructed as to resist great pressure from without or within, and while adapted for general use is particularly designed for use in connection with an air forcing and pressure apparatus, as hereinafter described.

In the accompanying drawings, Figure 1 is mainly a central vertical section of the apparatus. Fig. 2 is a plan view of the water-tank proper. Fig. 3 is a perspective view of one of the sector-shaped plates comprising the cover of the tank. Fig. 4 is a detail cross-section illustrating the manner of securing the sector-shaped plates together.

At a point below the source of water-supply I construct a water tank or receiver A and provide it with an air-tight cover B. Water is admitted to this tank through a pipe C, which is laid underground and extends to the higher source of water-supply. It is provided at c with a check-valve, which opens toward the tank, and at c' with a stop-cock, which may be operated by a vertical rod c'', arranged in a tube c', set in the ground. The valve or stop-cock c' enables the water to be cut off whenever desired, and the check-valve c prevents the reflow of water from the tank. A discharge-pipe D is also connected with the bottom of the tank and laid underground. It is likewise provided with a check-valve d opening outward. An air-pump E is connected by a pipe e with the top or highest portion of the conical cover B of the water-tank. This pump will be operated by any suitable means and may be located at any desired distance from the tank and at any desired elevation above the same. The body of the tank or cistern A is constructed of cement, and it is provided around its upper edge with a rabbet or shoulder a, upon which the edge of the metal cover B rests. The center of the cover B is supported upon the flanges f of a vertical post F, that is provided with a suitable base

f', set in the center of the tank or cistern A. The cover B is constructed in sections, which, as shown in Figs. 2, 3, are sector-shaped and provided with flanges b, formed by turning up the edges of each piece. These flanges b are 55 provided with perforations for receiving rivets. (See Fig. 4.) A thick layer of water-proof cement B' is applied over the entire cover B and serves to protect and cover the joints of the same as well as to exclude frost and 60 heat to a great degree, so that the water in the tank is kept comparatively cool in summer and comparatively warm in winter. The edges of the cover B are firmly yet detachably secured to the tank or cistern A by means of 65 long bolts b', which extend down through the cistern and are provided with nuts on the under side of the same. By this means and the cement cover I form an air-tight joint between the cover and the tank. 70

When the tank is entirely or partly filled with water, it is apparent that the latter may be forced out through pipe D and that the air pressure required for this purpose within the tank must correspond to the height to which 75 it is required to elevate the water.

It is obvious that the air-pump must be stopped and the air in tank allowed to escape in order to permit the tank to refill with water. The air escape may be effected by any 80 suitable means—as, for example, by the stop-cock with which the cylinder of an air-pump is commonly provided.

An air safety-valve is shown at G as an attachment of the tank. It may be set to operate at a pressure slightly greater than that required for elevating the water to the desired height, so that the air-pump can never be operated to apply undue pressure in the tank. 85

What I claim is—

1. The combination, with a water-tank having a rabbet at the top, of a cover whose edge rests in said rabbet, and bolts passing through said edge and through the body of the tank, substantially as shown and described. 95

2. The combination, with the tank proper and a central post having a base which is set in the tank proper and top flanges as described, of a cover resting at its center upon the said flanges and at its edge upon the top of the 100

tank, means for securing the cover in place, and a cement layer applied to the said cover, substantially as shown and described.

3. The combination, with the tank proper having a rabbeted edge and a central post having top flanges, of a cover supported at the center upon the flanges of the post and at its edge upon the rabbet of the tank, substantially as shown and described.
- 10 4. The improved water-tank, having a con-

cave body and a cover formed of sector-shaped pieces having upturned edges which are riveted together, and a layer of waterproof cement applied upon said cover so as to conceal and protect the joints, substantially as shown 15 and described.

JAMES TABB DONAHOO.
